United States Patent Office

Des. 203,663
Patented Feb. 8, 1966

203,663

RAILING

Louis Blum, 2312 Tilbury St., and William J. Horgan, Jr.,
1299 Folkstone Drive, both of Pittsburgh, Pa.

Filed July 28, 1965, Ser. No. 86,320

Term of patent 14 years

(Cl. D13—7)

FIG. 1

FIG. 2

FIG. 3

FIG. 1 is a perspective view of a railing embodying our new design wherein the shading on the rail represents conventional wood graining;

FIG. 2 is a side view of the railing of FIG. 1;

FIG. 3 is a bottom view thereof.

The railing is shown broken away to indicate an article of indeterminate length.

We claim:

The ornamental design for a railing, as shown and described.
